BRIDGING PLUG

George F. Turechek, Los Angeles, Calif., assignor
to Lane-Wells Company, Los Angeles, Calif., a
corporation of Delaware

Original application January 20, 1942, Serial No.
427,457, now Patent No. 2,382,455, dated Au-
gust 14, 1945. Divided and this application
May 19, 1945, Serial No. 594,708

8 Claims. (Cl. 166—13)

1

My invention relates to bridging plugs; that is, to devices which are lowered into a well casing to plug or close the casing at some point above the bottom of the well. This application is a division of my copending application, Serial No. 427,457, filed January 20, 1942, now Patent No. 2,382,455. Among the objects of my invention are:

First, to provide a bridging plug which sets or locks against movement in either direction and which incorporates a packing element to completely close and seal the casing;

Second, to provide a bridging plug which includes a novel slip and cone or wedging arrangement employing two sets of slips wherein a minimum axial movement of the slips along the casing wall is required in order to move the slips from their initial or retracted position to their set or locked position, and virtually no axial movement of the slips is required after engaging the casing to bring both sets of slips into locking engagement;

Third, to provide a bridging plug having confronting wedge members so arranged that slips mounted on each of the wedge members are urged into operating position by abutment shoulders provided on the other wedge member, so that as the wedge members are moved axially toward each other the slips are expanded;

Fourth, to provide a bridging plug which is so designed that the parts may be made of easily drillable or friable material, so that it may be drilled up if it is desired to remove the bridging plug; and

Fifth, to provide a bridging plug which is particularly designed to be lowered on a wire line and set by a wire line operated setting tool such as disclosed in Patent No. 2,266,382 issued December 16, 1941.

With the above and other objects in view, as may appear hereinafter, reference is directed to the accompanying drawings, in which:

Figure 1 is an elevational view of my bridging plug as it appears initially when being lowered into a well casing;

Figure 2 is an enlarged fragmentary longitudinal sectional view thereof taken through 2—2 of Figure 1;

Figure 3 is an enlarged transverse sectional view taken through 3—3 of Figure 2, showing particularly the clutch ring or locking ring;

Figure 4 is another transverse sectional view taken through 4—4 of Figure 1, showing particularly the slips and their expander wedges;

Figure 5 is an end elevational view of one of the

2

segmental retainer rings for the packing sleeve with one of the segments removed;

Figure 6 is an elevational view similar to Figure 1, showing the bridging plug set within a casing, the casing being shown fragmentarily and in section;

Figure 7 is a fragmentary longitudinal sectional view thereof taken through 7—7 of Figure 6;

Figure 8 is a transverse sectional view thereof taken through 8—8 of Figure 6, showing particularly the arrangement of the slips and their wedging members;

Figure 9 is a fragmentary longitudinal sectional view similar to Figure 7 showing a modified form of slip and wedging means, the view being taken substantially through 9—9 of Figure 10;

Figure 10 is a transverse sectional view thereof taken through 10—10 of Figure 9; and

Figure 11 is an elevational view of one of the modified slip members.

My bridging plug includes a mandrel or body 1 which is tubular in form but is closed at its lower end by a head member 2. The mandrel 1 is connected by a shear pin A or other suitable means to a setting tool member B, indicated fragmentarily in Figure 2. The head member 2 may be provided with equalizing or circulating valves such as shown in Patent No. 2,249,172 issued July 15, 1941.

The upper end of the head member 2 forms a frusto-conical shoulder 3 around which fits a segmental retainer ring 4 comprising a series of segmental members having circumferentially overlapping tongues 5 and 6 which remain overlapped when the ring is expanded into contact with the casing, as shown in Figure 6. The retainer ring 4 is provided with an annular groove 7 which receives a tie wire 8 for initially holding the segments comprising the ring around the mandrel 1. One end of the ring is shaped to conform to the frusto-conical shoulder 3 while the other end of the ring is provided with an inner bevel 9 and an outer bevel 10 which coact with a similarly beveled end of a packing sleeve 11.

The packing sleeve is more fully disclosed in Patent No. 2,249,171 issued July 15, 1941. The upper end of the packing sleeve coacts with a second segmental retainer ring 4.

Above the packing sleeve the mandrel receives a pair of slip expanders 12 and 13. The lowermost slip expander 12 forms at its lower end a frusto-conical shoulder 14 similar to the shoulder 3 which coacts with the upper segmental retainer ring 4.

The slip expanders 12 and 13 are provided with frusto-conical wedging portions 15 and 16, respectively, which converge toward each other. These portions are provided with axially directed slots 17 and 18, respectively, which form corresponding axially directed tongues 19 and 20. The tongues 19 of the lower slip expander fit into the slots 18 of the upper slip expander and, similarly, the tongues 20 of the upper slip expander fit into the slots 17 of the lower slip expander.

The lower slip expander 12 receives a set of slips 21 which ride upon the tongues 19 and fit into the slots 18 of the upper slip expander, abutting against the upper extremities of the slots. Similarly, a set of slips 22 ride upon the tongues 20 of the upper expander and fit into the slots 17 abutting the lower extremities thereof.

When the slip expanders are moved axially toward each other the lower slip expander urges the slips 22 of the upper slip expander upwardly and outwardly thereon and, similarly, the upper slip expander urges the slips of the lower slip expander along the tongues 19.

The slips 21 and 22 overlap axially when in their initial position and are provided with channels 23 which align circumferentially so that a single tie wire 24 may be wrapped around both sets of slips to hold them against their respective expanders. As best shown in Figures 2 and 7, the slip 21 has saw-tooth shaped serrations facing in a direction away from the tapering surface 15 of the slip expander 12 and the slip 22 has similarly shaped serrations which face in a direction away from the tapered surface 16 of the slip expander 13. By this arrangement any tendency toward axial movement of the plug after setting of the slips will tend to cause further expansion of the slips.

A sleeve 25 is screw-threaded to the upper slip expander 13 and defines therewith an internal channel 26 which receives a clutch ring or locking ring 27. The clutch ring is provided with internal teeth which are adapted to coact with corresponding teeth 28 provided on the mandrel when the slip expander 13 is forced downwardly thereon in the course of expanding the slips and packing sleeve. In order to prevent accidental movement of the slip expanders 12 and 13 these may be initially secured to the mandrel by shear pins 29.

Operation of my bridging plug is as follows: The bridging plug is lowered by any suitable setting tool capable of pulling upwardly on the mandrel 1 and forcing downwardly on the sleeve 25. Upon being lowered to the desired position, the bridging plug is set by pulling upwardly on the mandrel and forcing downwardly on the sleeve 25. This compresses the packing sleeve until the shear pins 29 give way, thereupon the slip expanders move toward each other, breaking the tie wire 24.

The packing sleeve, in compressing, exerts sufficient force on the segmental retainer rings 4 to cause these rings to expand outwardly against the casing as shown in Figure 6. The retainer rings, when so expanded, serve to prevent axial flow of the material comprising the packing sleeve. In this connection, it should be noted that the packing sleeve is made of rubber or, more preferably, "neoprene," or similar rubber-like material unaffected by well fluids. However, it is known that these materials have a tendency to "cold flow" and it is desirable to close the space at the end of the packing sleeve as much as possible.

It will be noted that the slips are guided on both sides, as well as their ends, by the slots in which they fit, so that they remain substantially equally spaced around the bridging plug, as shown in Figure 8. It will also be noted that it is not necessary for either set of slips to slide along the casing before the other set of slips come into contact therewith, but both sets of slips come into contact with the casing virtually simultaneously. This assures adequate engagement by both sets of slips so that the bridging plug is securely locked against either upward or downward movement, and even though the forces against the bridging plug should alternate so that the pressure is first in one direction and then in the other there is no appreciable play or slack to cause the bridging plug to work loose.

Reference is now directed to Figures 9, 10 and 11. The structure here illustrated is essentially the same as the previously described structure, with the exception that the wedging frusto-conical members 31 are not provided with tongues and slots; instead, the slips 32 are provided with tongues 33, as shown in Figure 11. The slips 32 are initially positioned so that the tongues of one set of slips fit between the tongues of the other set of slips. The upper frusto-conical member engages the extremities of the tongues of the lower set of slips, while the lower frusto-conical member engages the tongues of the upper set of slips. With this arrangement a greater slip area may be provided than is possible in the first described structure, for the slips being axially displaced may overlap circumferentially, as shown in Figure 10. The slips, as in the first described structure, are provided with channels 34 which receive tie wires 35.

Operation of the structure shown in Figures 9, 10, and 11 is the same as in the first described structure, that is, each frusto-conical member performs two functions: it coacts with its own set of slips and at the same time urges the other set of slips upon the other frusto-conical member. The slips preferably completely fill the circumference of the bridging plug so that they serve to hold each other in position; that is, the tongues of one set of slips are guided by the other set of slips.

Various changes and alternate arrangements may be made within the scope of the appended claims, in which it is my intention to claim all novelty inherent in the invention.

I claim:

1. A well tool comprising: a mandrel; a resilient packer sleeve encircling said mandrel; a circumferentially segmented expandable ring around said mandrel at each end of said packer sleeve, each expandable ring being initially positioned in abutment with the adjacent end of said packer sleeve and being free to slide radially and to rotate with respect to said packer sleeve, each expandable ring having a frusto-conical bore portion outwardly diverging in a direction away from the packer sleeve; an expanding member slidable on said mandrel adjacent that end of each expandable ring which is directed away from the packer sleeve, each expanding member having a frusto-conical portion insertible into the frusto-conical bore portion of its adjacent expandable ring in wedging engagement therewith, said rings thereby being expandable by said expanding members into continuous sealing contact with the inside surface of a surrounding casing, and thus together with said expanding members sealing the annular space between the casing and said man-

drel at the ends of said packer sleeve to confine said packer sleeve axially therebetween; and means to actuate said expanding members to expand said rings and packer sleeve.

2. A well tool according to claim 1 in which said circumferentially expansible rings comprise a plurality of overlapping step-cut circumferential segments.

3. A well tool according to claim 1 in which said circumferentially expansible rings comprise a plurality of overlapping step-cut circumferential segments and yieldable means initially retaining said segments in assembled and unexpanded position on said mandrel.

4. A well tool comprising: a mandrel; a resilient packer sleeve encircling said mandrel; a circumferentially expansible ring around said mandrel at each end of said packer sleeve, each expansible ring being initially positioned in abutment with the adjacent end of said packer sleeve and being free to slide radially and to rotate with respect to said packer sleeve, each expansible ring having a frusto-conical bore portion outwardly diverging in a direction away from the packer sleeve; an expanding member slidable on said mandrel adjacent that end of each expansible ring which is directed away from the packer sleeve, each expanding member having a frusto-conical portion insertible into the frusto-conical bore portion of its adjacent expansible ring in wedging engagement therewith, said rings thereby being expansible by said expanding members into continuous sealing contact with the inside surface of a surrounding casing, and thus together with said expanding members sealing the annular space between the casing and said mandrel at the ends of said packer sleeve to confine said packer sleeve axially therebetween; and means to actuate said expanding members to expand said rings and packer sleeve.

5. A well tool comprising: a mandrel; a resilient packer sleeve encircling said mandrel; a circumferentially expansible ring around said mandrel at one end of said packer sleeve, said expansible ring being initially positioned in abutment wth the adjacent end of said packer sleeve and being free to slide radially and to rotate with respect to said packer sleeve, said expansible ring having a frusto-conical bore portion outwardly diverging in a direction away from said packer sleeve; a ring expanding member slidable on said mandrel adjacent the end of said expansible ring which is directed away from said packer sleeve, said ring expanding member having a frusto-conical portion insertible into the frusto-conical bore portion of said expansible ring in wedging engagement therewith, said expansible ring thereby being expansible by said expanding member into continuous sealing contact with the inside surface of a surrounding casing, and thus together with said expanding member sealing the annular space between said mandrel and the casing at said one end of said packer sleeve to confine one end of said packer sleeve; and means to actuate said expanding member to expand said expansible member.

6. A well tool comprising: a mandrel; a resilient packer sleeve encircling said mandrel; a circumferentially expansible ring around said mandrel at one end of said packer sleeve, said ring being initially positioned in abutment with said one end of said packer sleeve and being free to slide radially and to rotate with respect to said packer sleeve; a ring expanding member slidable on said mandrel adjacent that end of said expand-

sible ring which is directed away from said packer sleeve, said ring expanding member having a frusto-conical outer surface which diverges in a direction away from said expansible ring, said frusto-conical outer surface being insertible into the bore portion of said expansible ring in wedging engagement therewith, said ring thereby being expansible by said expanding member into continuous sealing contact with the inside surface of a surrounding casing and thus together with said expanding member sealing the annular space between said mandrel and the casing at said one end of said packer sleeve to confine said one end of said packer sleeve; and means to actuate said expanding member to expand said expansible ring.

7. A well tool comprising: a mandrel; a resilient packer sleeve encircling said mandrel; an expansible ring around said mandrel at one end of said packer sleeve, said expansible ring having an outer frusto-conical surface outwardly diverging in a direction away from said packer sleeve, said outer frusto-conical surface being initially positioned in abutment with the adjacent end of said packer sleeve, said expansible ring being free to slide radially and to rotate with respect to said packer sleeve, and said expansible ring having a frusto-conical bore portion outwardly diverging in a direction away from said packer sleeve; a ring expanding member slidable on said mandrel adjacent that end of said expansible ring which is directed away from said packer sleeve, said ring expanding member having a frusto-conical portion insertible into the frusto-conical bore portion of said expansible ring in wedging engagement therewith, said ring and said one end of said packer sleeve being expansible by said expanding member into continuous sealing contact with the inside surface of a surrounding casing, and thus together with said expanding member sealing the annular space between said mandrel and the casing at said one end of said packer sleeve; and means to actuate said expanding member to expand said expansible ring and said packer sleeve.

8. A well tool comprising: a mandrel; a resilient packer sleeve encircling said mandrel and having an annular groove in one end surface thereof; a circumferentially expansible ring around said mandrel at said one end of said packer sleeve, said expansible ring having oppositely facing frusto-conical bore portions whose diameters increase in opposite directions leading outwardly of the ring and having a frusto-conical outer peripheral surface at the end of the ring adjacent said one end of said packer sleeve, said frusto-conical outer peripheral surface of said ring being initially positioned in said annular groove in said packer sleeve and said ring being free to slide radially and to rotate with respect to said packer sleeve; a ring expanding member slidable on said mandrel adjacent that end of said expansible ring which is directed away from said packer sleeve, said ring expanding member having a frusto-conical portion insertible into the adjacent frusto-conical bore portion of said expansible ring in wedging engagement therewith, said ring and said one end of said packer sleeve thereby being expansible by said expanding member into continuous sealing contact with the inside surface of a surrounding casing, said expansible ring together with said expanding member sealing the annular space between said man-

ndrel and the surrounding casing to confine said one end of said packer sleeve; and means to actuate said expanding member to expand said expandable ring and said one end of said packer sleeve.
